UNITED STATES PATENT OFFICE.

CARL ERIC ANDERSON, OF STRATFORD, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed September 11, 1923. Serial No. 682,096.

My invention relates to electric switches, and particularly to switches of the hill and valley type. The object of my invention is to provide a simplified and improved construction of the operating mechanism.

In the accompanying drawings—

Fig. 1 is a vertical section through a switch in which my invention is embodied in one form;

Fig. 2 is a section on the line 2—2, Fig. 1; and

Fig. 3 is a dropped perspective of certain elements of the switch mechanism.

As here shown I have applied my invention to a switch embodied in an electric lamp socket, but it will be readily understood that the mechanism is suitable for switches of various types, and that its utility is not limited to this particular fitting.

The structure shown comprises upper and lower insulating buttons 5 and 6 spaced apart to accommodate the switch mechanism. On the button 6 is the usual screw shell 7 electrically connected to the spacing bar 8

which carries one of the binding screws (not shown). The center contact 9, also mounted on the button 6 is connected by the rivet 10 to a switch contact 11 on the opposite face of the button. Underlying the spacing bar 12 which carries the binding screw 13

is the base of a cooperating switch contact 14, arranged diametrically opposite the contact 11. Adapted to span the contacts 11 and 14 is the rotary switch bar 15, freely

mounted on the switch spindle 16 and subject to the throw of the torsion spring 17, one end 18 of which engages the switch bar, while the opposite end 19 engages the driving plate 20 fast on the spindle 16.

The switch bar travels a hill and valley course, the hills of which form detents over which the switch bar rises during the stressing of the switch spring 17, followed by a rapid movement into the succeeding valleys

upon its escape from the crests of opposite hills. Two opposite hills 21 and 22 are formed by arcuate bosses on the face of the button 6, the detent face of each boss lying practically at right angles to the course of the switch bar.

The intervening hills are formed by flanges 23 and 24 abruptly offset from the margins of the switch contacts 11 and 14 and forming detents, which like the

hills 21 and 22, hold the switch bar 15 against rotation during the initial stressing of the switch spring 17. The incline of the detent faces of the several hills is so sharp that the permissible stressing of the spring 17 is not in itself sufficient to cause the switch bar to ride up the detents until it escapes their crests. To effect this necessary rise of the switch bar, I provide means for positively lifting it to the crests of the detaining hills.

The particular means employed for this purpose according to the present invention, constitute integral laterally extending arcuate wings 25 downwardly inclined toward the base 6 and extending below the plane of the bar 15. Cooperating therewith is a lifting cam 26 fast on the spindle 16 and having two arcuate notches 27 and 28 adapted to receive the wings of the switch bar. On the rotation of the spindle 16, the radial margins 29 and 30 of the notches in the cam plate engage the lower faces of the wings 25 and lift the switch bar to the crest of the detaining hills, while the switch spring 17 is simultaneously stressed.

The operation of this mechanism effects a result substantially like that of the construction shown in the Renholdt Patent No. 1,400,376.

The cooperating switch bar and cam elements of the present structure are, however, much simpler to manufacture, and are more certain in operation. Thus, the cam 26 comprises merely a flat stamping, necessitating no forming action for the cam surfaces. Similarly the cooperating wings 25 of the switch bar are merely downwardly inclined through a relatively small angle instead of being offset substantially at right angles to the plane of the switch bar, as in the Renholdt construction, with resultant weakening and danger of breakage. Less exactitude of construction is necessary, moreover, since the engagement between the cam and the switch bar wings, is not an edge engagement, as in the Renholdt construction, but a face engagement between the lower surface of the wings 25 and the side margins, 29 and 30, of the notches 27 and 28 in which the wings play.

The operation of the mechanism is obvious. The switch bar 15 normally rests upon

the cam 26 in such position that the wings 25 fully enter the opposite notches 27 and 28 in the cam. Upon the rotation of the cam, while the switch bar is detained by the hills of its course, the side margins 29 and 30 of the notches, coming into engagement with the lower faces of the wings 25, lift the bar to the crests of the detaining hills. This action of the cam compresses the spring 17, which is at the same time placed under additional torsional stress by the rotation of the spindle. Consequently, as soon as the switch bar reaches the crests of the detaining hills, it is not only rotated through the torsional action of the spring 17, but is forced downward into the succeeding valleys of its course by the expansion of the spring, and thus halted by the detent faces of the succeeding hills. As the switch bar rotates and is depressed into the valleys, the cam wings 25 run down into the notches 27 and 28 of the cam, thus resuming the position illustrated in Fig. 1.

The cam 26 may be secured to the spindle 16 in any desired fashion. I have indicated a non-circular central aperture 31 which engages the non-circular lower end 32 of the spindle for rotation therewith.

The drive of the spindle 16 may be accomplished in any suitable fashion. I have indicated a ratchet drive by the ratchet disc 33 associated with the carrier 34 for one end of a pull chain 35, such as is common in pull switch construction. The teeth of the ratchet 33 engage the arms 36 of the drive plate 20 fast on the spindle 16, and thus rotate the latter. Surrounding the spindle is a ratchet return spring 37, one end of which engages the ratchet disc 33, while its opposite end is engaged in an adjustable abutment 38 seated in a squared recess in the button 5 as is well understood in the art. The abutment 38 forms a bearing for one end of the spindle, while its opposite end extends into a bushing 39 freely resting in a well 40 in the button 6. The shoulder 41 on the spindle overlies the cam 26 and the

latter, resting on the bushing 39 forms the step bearing for the spindle.

The particular shapes of the cam 26, wings 25 of the switch bar, and of other parts, may be modified in various ways without departing from what I claim as my invention.

I claim—

1. An electric switch comprising a rotary spindle, a sheet metal washer rotating therewith and having circumferentially spaced notches in its periphery, in combination with a sheet metal switch bar mounted freely on the spindle for displacement in axial direction and for rotation on said spindle, said switch bar having a surface normally resting against the face of the washer, portions of said surface being warped toward the washer and into the peripheral notches in the latter and bearing against the following margins of said notches together with a spring stressing the switch bar toward the washer and serving to impart a forward throw to the switch bar after predetermined rotation of the spindle to cause longitudinal displacement of the switch bar thereon incident to the engagement of said warped surfaces in the notches of the washer.

2. In an electric switch, a switch bar having lateral wings warped out of the plane of the bearing surface of the bar, and a marginally notched flat washer against which the switch bar bears and into the notches of which the switch bar wings enter to present the warped surface of the bar to the margin of the notch at the following end of the latter on the rotation of the washer with respect to the bar, spring means urging the adjacent faces of the bar and washer toward each other, detents engaging the bar, and means for rotating the washer to effect the displacement of the bar out of detaining engagement with the detents.

In testimony whereof I have signed my name to this specification.

CARL ERIC ANDERSON.
